D7157

2-3-1874

WARD'S
NEW
LAW

UNITED STATES PATENT OFFICE.

SAMUEL WARD, OF BOSTON, MASSACHUSETTS.

DESIGN FOR LABELS.

Specification forming part of Design No. **7,157**, dated February 3, 1874; application filed January 8, 1874.
[Term of Patent 14 years.]

To all whom it may concern:

Be it known that I, SAMUEL WARD, of the city of Boston, county of Suffolk and State of Massachusetts, have invented a Design for Labels, of which the following is a specification:

The nature of my design is fully represented in the accompanying print, to which reference is made.

A represents an ornamental design or tablet having square corners at the top, and being pointed in the upper center, and having ribbons which inclose a center piece, nearly oval in form, and then meet together at the bottom of the design. B represents a band or ribbon running laterally across the central portion of the oval-shaped center piece, which is inclosed by the ribbons attached to the tablet. C represents Egyptian ornamentation, which surrounds the whole design, and which in turn is again surrounded by a plain-line border.

I prefer to print it in colors, but do not consider the colors to be an essential feature in my design.

What I claim as my invention is—

A design for a label composed of an ornamental design or tablet having square corners at the top, pointed in the upper center, and having ribbons which meet together in the center at the bottom of the design, and which surround and inclose a center piece nearly oval in form, running laterally across which is the band or ribbon B, above mentioned, the whole being surrounded by Egyptian ornamentation and a plain-line border, substantially as shown.

SAMUEL WARD.
